UNITED STATES PATENT OFFICE.

JAMES R. McNABNEY AND CHARLES E. ANDREWS, OF KOKOMO, INDIANA.

GATE.

1,298,072.

Specification of Letters Patent. Patented Mar. 25, 1919.

Application filed October 25, 1918. Serial No. 259,674.

To all whom it may concern:

Be it known that we, JAMES R. McNABNEY, and CHARLES E. ANDREWS, citizens of the United States, residing at Kokomo, in 5 the county of Howard, State of Indiana, have invented a new and useful Gate, of which the following is a specification.

The device forming the subject matter of this application is a gate, and the invention 10 aims to provide a structure of the class above mentioned, which can be adjusted vertically, when it sags, the gate being vertically adjustable for other purposes, such as to permit the passage of small stock but acting 15 at the same time as a barrier for larger stock.

The invention aims to provide novel 20 means whereby the posts and rails of the gate may be held together, to permit a vertical adjustment of the gate, without the use of screws, bolts, or the like.

It is within the province of the disclosure to improve generally and to enhance the utility of devices of that type to which the present invention appertains.

25 With the above and other objects in view, which will appear as the description proceeds, the invention resides in the combination and arrangement of parts and in the details of construction hereinafter described 30 and claimed, it being understood that, within the scope of what is claimed, changes in the precise embodiment of the invention shown can be made without departing from the spirit of the invention.

35 In the accompanying drawings:—

Figure 1 shows in side elevation, a gate 40 constructed in accordance with the invention; Fig. 2 is a section taken through the upper end of the end post; Fig. 3 is a section 45 taken through the end post adjacent to one of the cross rails; Fig. 4 is a section taken through the intermediate post at one of the cross rails; and Fig. 5 is a section taken through the intermediate post at one 50 of the turnbuckles.

In carrying out the present invention there are provided end posts 1, one of which, is supplied with any suitable means 2 whereby the gate may be suspended for horizontal 55 swinging movement. In the inner edges of the end posts 1, concaved seats 3 are formed. The invention includes an intermediate post 4 having oppositely flaring passages 5. Rails 6 extend through the passages 5 of the posts 4 and have rounded ends 7 mounted to rock 55 for adjustment in the seats 3 of the end posts

1. Diagonal turnbuckles 8 are located on opposite sides of the gate and pass through flared recesses 9 formed in the posts 1 near to the ends thereof, the recesses 9 coöperating with enlarged openings 10 in the outer edges of the posts 1, there being shoulders 11 at the inner ends of the openings 10. Bearings 12 are seated in the openings 10 in abutment with the shoulders 11 and are held 60 against rotation in the openings, the bearings having concaved seats 14 in which convexed washers 15 are mounted to rock for adjustment, the ends of the turnbuckles passing through the bearings 12 and through the 70 convexed washers 15. Flat washers 16 abut against the convexed washers 15 and there are nuts 17 on the ends of the turnbuckles, the nuts coöperating with the flat washers.

From the foregoing description it will be 75 observed that the ends of the turnbuckles 8 are so assembled with the ends of the posts 1 as to have the necessary play or movement, during the adjustment of the gate, as hereinafter described. It is to be understood, however, that the ends of the turnbuckles 8 may be connected to the posts 1 in any desired way. A turnbuckle 18 extends longitudinally of the gate and passes through an oppositely flaring passage 19 in the intermediate post 4. The ends of the turnbuckle 85 18 are pivoted by means of eyes 20, to eye-bolts 21 carried by the end posts 1.

Obviously, by adjusting the turnbuckles 8, the gate may be raised or lowered at its 90 free swinging edge, the rounded ends 7 of the rails 6 rocking in the seats 3 of the posts 1, the passages 5 in the intermediate post 7 being so shaped that the intermediate portions of the rails 6 may have the necessary 95 movement during the adjustment of the gate, the function of the passage 19 with respect to the turnbuckle 18 being understood readily in view of what has been said hereinbefore in connection with the ends 7 of the rails 6 100 and the seats 3 in the posts 1.

The free edge of the gate may be raised and lowered, either for the purpose of truing up the gate vertically, or for the purpose of so adjusting the gate that hogs and 105 other small animals may pass beneath the gate, the gate, nevertheless, serving as a barrier for cattle and relatively large animals. After the gate has been elevated, or adjusted as above described, the turnbuckle 110 18 may be tightened up, to aid in holding all of the parts of the gate together firmly.

Having thus described the invention, what is claimed is:—

1. A gate comprising end posts having seats in their inner edges; an intermediate bar having transverse passages; rails having their ends abutting against the posts within the seats and mounted to rock therein, the rails having their intermediate portions mounted to rock in the passages; and diagonal, longitudinally adjustable tightening devices having their ends assembled with the ends of the posts.
- 5 2. A gate comprising end posts having seats in their inner edges; rails having their ends mounted to rock in the seats; diagonal,
- 10
- 15

longitudinally adjustable tightening devices having their ends assembled with the ends of the posts; and a longitudinally adjustable tightening device disposed approximately parallel to the rails, and having its ends assembled with the posts, between the ends of the posts.

In testimony that we claim the foregoing as our own, we have hereto affixed our signatures in the presence of two witnesses.

JAMES R. McNABNEY.
CHARLES E. ANDREWS.
